George W. Slater

UNITED STATES PATENT OFFICE.

GEORGE W. SLATER, OF NEW HAVEN, CONNECTICUT.

SHIP'S STOVE.

Specification of Letters Patent No. 26,528, dated December 20, 1859.

To all whom it may concern:

Be it known that I, GEORGE W. SLATER, of New Haven, in the county of New Haven and State of Connecticut, have invented a new and useful Improvement in Stoves for Ships; and I do hereby declare that the following is a full, clear, and exact description of the same, reference being had to the annexed drawings, making a part of this specification, in which—

Figure 1, is a side sectional view of a stove with my invention applied to it, taken in the line x, x , Fig. 3. Fig. 2, is a transverse vertical section of ditto, taken in the line x', x' , Fig. 3. Fig. 3, is a plan or top view of ditto partly in section.

Similar letters of reference indicate corresponding parts in the several figures.

This invention relates to an improvement in a stove to be used on shipboard for which Letters Patent bearing date January 6th, 1857, were granted to Daniel S. Beardsley in connection with John D. Umberfield, and of which Letters Patent I am now the sole assignee.

The invention consists in hanging the stove aforesaid by means of adjustable or independent thimbles, substantially as hereinafter fully described, whereby said thimbles may be cast separately instead of with the whole flue as formerly and perfect joints obtained as well as more durable ones, the invention also admitting, of a more ready adjustment or fitting up of the stove.

To enable those skilled in the art to fully understand and construct my invention I will proceed to describe it.

A, represents a stove which may be of any suitable form and designed either for cooking or exclusively heating purposes. In the drawings an ordinary rectangular cook stove is represented. This stove A, like the patented one previously alluded to, is suspended in a swinging frame B, a transverse half a , of which is a flue connected with an upright stationary flue or pipe C', by a hollow joint D. The stove is also suspended to the frame B, by hollow joints E, E, which form a communication between the stove and the flue a . By suspending the stove in this manner, it, like the compass box is permitted to retain a proper position,—the swinging frame B, and jointed connections of the stove to it compensating for the rolling of the ship.

The joints D, E, E, which constitute my invention are formed each of two distinct parts to wit, thimbles b , and sockets c . The thimbles are simply short tubes cast with a flanch d , at their outer ends, said flanches having dove-tail edges and fitted in dove-tail grooves in the flue a , see Fig. 3. This method of attaching the thimbles to the flue a , prevents any lateral displacement of the same and at the same time admits of their ready adjustment to and removal from the flue a , when necessary. The thimbles b , all communicate with the flue a .

To the stove A, at each side a socket c , is attached to receive the thimbles. These sockets are cast separately and they are bolted to the stove so as to connect with its flue g , as shown clearly in Fig. 2. The sockets c , are of such a size as to receive the thimbles b , of the joints E, E, said thimbles being allowed to turn freely therein. The thimble b , of the joint D, works on the socket c , attached to the flue C.

From the above description it will be seen that in case of wear or breakage, either the thimbles or sockets may be detached and replaced by new ones, and it will also be seen that as these parts are cast separately they may be of a finer and more durable material than the other parts of the stove and also may be cast perfectly. In the original stove the thimbles and sockets were cast with the flue a , and stove A, and consequently in case of any imperfection in either thimble or socket, all the other parts required to be re-melted in fact they were worthless except as old metal. By this invention perfect joints are insured and when worn by use or in case of being injured in any way they may be readily repaired. The half of the frame B, corresponding with the flue portion a , has an ordinary joint h .

Having thus described my invention what I claim as new and desire to secure by Letters Patent, is,

Forming the joints C, D, D, of the thimbles b , and sockets c , attached respectively to the swinging flue a , stove A, and stationary flue C', substantially as and for the purpose set forth.

GEORGE W. SLATER.
